Specification of Letters Patent.

Patented May 4, 1915.

Application filed May 24, 1913. Serial No. 769,558.

To all whom it may concern:

Be it known that I, JAMES POWERS, a citizen of the United States, residing in New York city, in the county of New York and State of New York, have invented certain new and useful Improvements in Perforating-Machines, of which the following is a specification.

My present invention is a simplification of and an improvement upon card-perforating machines such as described in my prior United States Patents 992245 and 992246, and enables me to make machines for such general purposes which are simpler, cheaper, more compact, durable and reliable; to greatly improve the action; and to very greatly reduce the number of keys which the operator must remember the location of, locate, strike, and to arrange and space them accessibly and conveniently for finger-operation. In said patents I illustrate a keyboard with twenty-four rows of twelve keys each, or two hundred and eighty-eight keys amongst which the operator must locate and strike the keys necessary to form a card perforation record. In the present machine I have but thirteen striking keys of which only ten need be struck to record a series of facts, the other keys comprising a skip-key and classification keys. These improvements reduce the strain on the operator and his labor and the percentage of errors and lost work, and thereby quicken and greatly increase the output and make it more reliable.

My improvements may be generally described as consisting in dividing the action into two parts, namely, punch actions and key actions; in reducing the number of key actions to the number of punch actions in one punch series, plus a skip-key, all conveniently combined in one key mechanism; in adapting this key mechanism to select and cause the operation of any punch in any of the series of punches by mounting it on a suitable automatically-fed carriage; and in improvements in the arrangement and transmission rendered practicable by the novel actions.

In the drawings, Figure 1 is a side elevation with certain parts broken out; Fig. 2 is a transverse section of the machine; Fig. 3 is a plan; Fig. 4 an enlarged detail of the punch-action switch, mounted; Fig. 5 a like

view of the switch, dismounted; Fig. 6 is a view of a switch-spring; and Fig. 7 is an enlarged detail of the key-carriage feed mechanism, showing the shaft-head.

To facilitate comparison of this with the patents referred to, reference characters hereof refer to parts like, or having functions like, the members designated by the same characters in said patents.

I provide a frame comprising a base 1 and a basket 2, which supports the upper machine members. At opposite sides of the base 1 I mount a card-supply hopper 90 and a record-card bin 130 and between them a card-feed, generally designated by 97, which comprises suitable rolls, operably connected with the main shaft; and beneath the supply hopper 1 I locate a card picker 91, also operably connected with the main shaft by a cam-and-link gearing 93, and adapted to pick cards one at a time from the hopper 90 and advance them to the card-feed 97 from which they are fed between the die-plate 24 and the guide-plate 23 for perforation, and subsequently to the bin 130.

On the base 1, I revolvably mount a transmission comprising a main shaft 15 controllably connected with a source of power and armed with suitable cams and driving members, and operably connected by cams, links and otherwise with the power driven machine members; none of which constitutes part of my present invention and therefore need not be described. On the base 1 I mount a vertically-reciprocating die box 21 operably connected with the main shaft 15 and guided on the base as shown in said patents. On the die-box 21 I mount, separated by a card-way, a die plate 24 and a guide plate 23, and in said plates respectively, I make a plurality of series of registering die holds and guide holes for the punches 50. Above the upper limit of the guide-plate motion, I mount on the basket 2 a punch-support plate 5 likewise perforated, which normally supports and positions the punches 50, whose heads 50^a rest on said plate save when they are lifted, as hereafter described.

The punch heads, 50^a, are rectangular to prevent the punches from turning, and lie and move between transverse plate separators, 5^a, of a grill formed of said separators and lateral bars 5^b to which their

ends are fastened and by whose ends the grill and said separators are fastened (screwed) to the basket 2, the separators being thus adapted to be readily bench-assembled and positioned and set, as a unit, in the machine. The punch shanks are flattened to form retraction shoulders 50^b; and retraction bars 23^a located adjacent to the series of punches and secured to the guide plate 28 by angle bars 23^b are adapted to retract elevated punches, when the punch box 21 descends, by the engagement of the bars 23^a with the shoulders 50^b of the raised punches, which are always in position to engage said bars because the punches are prevented from turning, as aforesaid.

On the basket I mount a pair of action plates 8, perforated with a plurality of series of action-rod holes 8^a for divergent punch-action rods 50^c corresponding with the punches 50, said holes being necessarily formed at varying angles, for the several rods and therefore ovals with uniform minor and varying major axes, and spaced wider in the upper than in the lower plate.

The essence of my invention consists in the key-action S and punch-action P. To support the former, I provide two lateral rail-rods, 2^a fixed in and uniting the cheeks 30 of the basket 2; and on said rods I mount a wheeled carriage, S¹ formed of cheeks, S² parallel with and at the sides of the machine, and united by a pair of deck plates S³ and S⁴, the upper of which, S⁴, has a 35 longitudinal, outward extension constituting the lower key-plate to which the upper key-plate S⁵ is fixed by posts S⁶. The carriage S¹ is mounted on the rails 2^a by wheels, S⁷.

Each key-action, S, comprises a stem, S¹¹, 40 which slides in registering holes in the key-plate S⁵ and deck plate S⁴, has a head (on which its character may be marked) and a neck S¹² between said plates; a key-lever, S¹³, which is pivoted on a stud, S¹⁴, fixed in 45 the deck plate, and whose slotted free end engages said neck S¹² of the key-stem; a pin S¹⁵ formed with an upper head and a reduced, lower pin, and mounted in registering holes in the deck plates S³, S⁴; and a 50 spring S¹⁶, strained between the lower plate S³ and the pin head holds it up into permanent engagement with the key lever S¹³, and thereby holds up the key lever and stem.

The key-pins S¹⁵ are arranged in a transverse line and severally corresponding with punch rods of the several punch-series; and for convenient operation the key stems S¹¹ and their heads are located off the machine axis, bunched in three rows of four keys 60 each and finger spaced, about like typewriter keys. Because of these arrangements, the key levers are bent or offset in plan and (being thin bars) their free ends are twisted a quarter turn and slotted, to engage the necks S¹² of the stems S¹¹.

The carriage S¹ is spring-fed by means of a spring confined in a drum, S²¹, which is connected with the carriage by a cord or chain S²². When a record key is struck it causes the carriage to be released so that the carriage will be pulled forward by the spring drum S²¹ and cord S²²; and its advance is limited by an escapement E adapted to be operated by each record key action and also by a skip-key action, to be described.

The escapement E comprises a longitudinal rack E¹ fixed on the basket 2; a transverse rock shaft E² revolvably mounted in the carriage cheeks S²; a ratchet wheel E³ and fixed thereto a pinion E⁴ in permanent engagement with said rack, said wheel and pinion being revolvably mounted adjacent to said rock-shaft; a compound pawl E⁶ connected with said shaft and adapted to engage release and reengage the ratchet wheel 80 and a spring E⁵ connected with the initial pawl E⁶¹ of said compound pawl.

The rock-shaft E² is located above the upper deck plate S⁴, its bearings are in lugs of the carriage cheeks S² and its near journal is formed on a shaft head E²², which is formed with an inner head E²³, counterbore E²⁴ and transverse slot E²⁵ and an outer die E²⁶ and tapped hole E²⁷. The shaft is centered in and angularly fixed with the shaft 95 head by entering its end into the counterbore E²⁴ and by a pin E²⁹, which extends through the shaft and lies in the slot E²⁵; it is axially fixed by a collar fixed to it, interior to its inner bearing, and is provided with a rocker- 100 arm E²⁰, which extends under and in contact with the twelve key levers S¹³, so that the depression of any of said levers will rock the shaft. Adjacent to the shaft head the shaft E² serves as fulcrum for the skip-key 105 lever S¹³⁰, which is positioned thereon by collars.

The shank of the shaft head extends through its bearing far enough to afford an outer bearing for the pivotally mounted initial release and engagement pawl E⁶¹ of the compound pawl E⁶, whose other final release hook pawl E⁶⁶ fits on the square die E²⁶ of the shaft head. A screw, E²⁸, engages the tapped hole, E²⁷, and retains the pawl on 110 the shaft head and the latter in its bearing. The initial pawl E⁶¹ is offset in plan so that its head may be pivoted on the shaft head and its tip engages the ratchet wheel, and in it I fix a pin E⁶², which extends over the 115 shank of the skip-key lever S¹³⁰ and serves as one abutment for the spring E⁵, which is strained between it and the carriage cheek; and adjacent to the shaft head I form a concentric slot, E⁶³. In the pawl E⁶⁵ which is 120 fixed to the rock-shaft, I fix a pin, E⁶⁶, adapted to engage said slot E⁶³.

When a key S⁵ is depressed its lever S¹³ depresses the rocker arm E²⁰ and rocks the shaft E² and the final pawl E⁶⁶, so that its 130

- hook will enter the path of the teeth of the ratchet wheel E^3 and prevent its rotation, but without, as yet, moving the initial pawl E^{61} , because at such times the pin E^{66} of the 5 pawl E^{65} moves freely in the slot E^{68} of the initial pawl, but as such motion of the rock shaft and final pawl are continued and completed, said pin E^{66} engages the end wall of the slot E^{63} , lifts the initial pawl E^{61} and 10 disengages it from the ratchet wheel, which is therefore very slightly rotated and arrested and retained by the hook of the pawl E^{65} , and so retained as long as any of said keys are depressed. The initial pawl is 15 loosely mounted on the shaft head, its play being sufficient so that when it is disengaged as aforesaid from the ratchet wheel, the spring E^5 pulls it out radially so far that its tip is angularly extended beyond the tooth-face from which it was just disengaged so 20 that if it were immediately returned toward engaging position its tip would ride on the back of said tooth, which prevents undesired carriage motions.
- 25 When the finger is lifted from the depressed key its spring S^{10} lifts it and its lever S^{13} and permits the rock shaft E^2 to be rocked by a spring E^{21} , which motion lifts the hook of the pawl E^{65} , releases the ratchet 30 wheel E^3 , and permits it to be rotated one tooth, (and the carriage S^1 to be correspondingly advanced) such motions being stopped by the initial pawl E^{61} , and caused by the traction of the feed drum and cord 35 S^{21} , S^{22} and the engagement with the rack E^1 of the pinion, E^4 , the latter being fixed to the ratchet wheel.
- Striking the skip-key S^{110} depresses the outer arm of its lever S^{130} without affecting 40 the rock shaft (because the rocker arm E^{20} does not extend under said lever) and raises its inner arm and the pin E^{62} and initial pawl E^{61} , disengages the latter from the ratchet wheel and permits the spring feed 45 to advance the carriage one tooth only, because the initial pawl flies back and stops the carriage the instant said key is released; but holding down said key holds said pawl disengaged and (because the final pawl E^{65} 50 is upheld by the key springs S^{16}) permits the carriage to be advanced until said key is released or until it is stopped by contact with a manually setable stop S^{46} , to be described.
- 55 I provide a manually setable skip-stop mechanism S^{40} to facilitate skipping card-lines which are not to be perforated. In the basket 2 I pivot, by its cylindrical ends, a lateral, rocking, rack bar S^{41} , on which I form a rack S^{42} and I fix to said rack bar a parallel rod S^{43} by links S^{44} , pinned to both. To the back of the rack bar I fix a rocker arm S^{45} and on the parallel rod I pivot a number of stops S^{46} , each having a convenient handle, and a pair of teeth S^{47}

adapted to engage the rack S^{42} and tapered on their engaging side so as to readily engage the rack teeth. In each stop S^{46} I provide a round-pointed setting pin S^{49} held up by a spring S^{48} and adapted to engage 70 grooves S^{50} in the parallel rod S^{43} .

As illustrated, the ratchet wheel E^3 and pinion E^4 have an equal number of teeth, and therefore when the pinion E^4 rolls one tooth along the feed rack E^1 , the 75 ratchet wheel E^3 rotates through one of its tooth-angles. The feed-rack E^1 , pivoted stop-rack S^{42} and the teeth of the stops S^{46} , have a common pitch, and the teeth are symmetrical on the stops, whose thickness equals 80 two such tooth-pitches. Therefore the cheeks of the stops coincide with the axes of teeth of the stop rack.

Normally the skip mechanism S^{40} is retained in disengaged position (Fig. 2) by 85 a spring S^{51} , with its rocker arm bearing on a roller, S^{52} , which is operably connected with and lifted by striking the skip-key S^{110} ; and when so lifted swings the mechanism S^{40} inwardly so that such of its stops 90 S^{46} as are set enter the path of a finger, S^{52} , fixed on the carriage S^1 and constitutes stops to its motion. The skip-key S^{110} and its lever S^{130} are connected with the roller S^{53} by a rock shaft S^{54} mounted in the carriage 95 S^1 and having rocker arms S^{55} and S^{56} , the latter connected by a link S^{57} with the active end of said lever, the roller being mounted on the former. This mechanism greatly reduces the strain and work of operation and 100 increases the output. Record cards contain many unperforated lines, often irregularly spaced. Normally it is inoperative; but (the stops S^{46} being properly set) it can be swung into action by depressing the skip-key and enables the operator to instantly skip blank card-lines and stop the carriage at those which are to be perforated.

Punch actions.—The several punch action series correspond with one another and with the record-key series of the key mechanism. Each punch action series comprises a series of the aforesaid punches 50; a series of diverging punch extension rods 50^r, slidably mounted in the plate-holes 8^a and having 110 their lower ends severally resting on the punch-heads and located between the guide plates 5^a above the positioning plate 5; and a series of switch-blocks 50^s, pivoted on a transverse, bar-shaped switch-bearer 50^c, 115 such switch bearer being supported and suitably spaced by separators on lateral rods 2^b fixed in the basket 2.

The switch blocks 50^s are substantially inverted truncated isosceles triangles stamped 120 of thin plate, pivoted adjacent to one of their basal angles, with the pivots directly in the prolongations of the path followed by the corresponding punch-extension rods 50^r when the die-box 21 125

is lifted and to one side of the longitudinal, but in the transverse, planes of motion of the key-pins S^{15} . Said switch blocks normally hang with the free sides of their bases in paths followed by key pins S^{15} when the carriage locates them coaxingly and they are depressed; and with the points of said blocks depending below the bearers 50^c and to one side of the paths of the punch-extension rods 50^r .

A key pin S^{15} operates a switch block 50^s , by striking and depressing the free side of its base, and swinging its point between its pivot and the upper end of the corresponding punch-extension rod, into its path. If then, the die-box 21, containing a card to be perforated, be lifted, the punch-actions P , whose switch-blocks have not been set by key-pins, are supported by the card and, because they do not find switch-blocks in the paths of their extension rods, move freely with the die-box and do not punch the card; but those punch actions whose switch-blocks have been set are stopped thereby and punch the card.

In card-accounting there are many facts common to all the cards of a series, and machines of this general character embody means to manually fix the actions corresponding with such facts before, and to so retain them, during the perforation of a card-series. I provide apparatus for such purposes which is much simpler, cheaper and more convenient than any heretofore used, and which consists of a spring 50^x , preferably a hook-shaped plate, detachably united to the switch block, connected with a suitable abutment and adapted to retain the switch block in operative position (Figs. 3, 4, 5 and 6). The preferred mode of attaching the spring 50^x to the switch block is to slot the latter and make the spring of rectangular section adapted to fit closely in the slot; the maximum length and durability of spring being obtained by locating the slot in the base of the switch block, and contracting the loop of the hook so that it will not foul the key-pin.

In the operation of the machine a card is fed and located between the die and guide-plates 24 and 23, under the punches 50 ; the operator permanently sets those switch blocks 50^s which correspond with facts common to all the records of the series by putting springs 50^x on them; properly sets stops S^{46} of the skip mechanism S^{40} for skipping recurring blank lines; pushes the carriage back to its initial limit; strikes the proper key of the key action S to set the switch block corresponding with the first fact to be recorded, which causes the release of the carriage and its automatic advance to coact with the succeeding punch-action P ; and continues to strike such keys, set switch

blocks in the successive punch-actions and skip blank spaces and causes the advance of the carriage until switch blocks have been set corresponding with all the facts to be recorded; whereupon he presses the clutch knob, 39, and throws in the clutch, which causes the transmission to operate and lift the punch box 21. Those punch-actions P whose switch-blocks 50^s have not been set, move freely and do not perforate the card; but those whose switch blocks have been set are thereby arrested and do perforate the card as it is lifted in the die-box 21.

After the card has been perforated, a retractor, F , advances transversely, adjacent to the switch-bearers 50^c , returns all the switch-blocks 50^s to their normal inoperative position and itself returns to normal position; and while it is so returning, those switch blocks to which springs, 50^x have been affixed are thereby returned to operative position.

The retractor F comprises a pair of longitudinal rock shafts F^1 mounted in bearings in the basket 2 and each having near its ends a pair of equal rocker arms F^2 connected by rods F^3 , said rods being connected by transverse links F^4 , through which extend a series of retracting rods, F^5 , corresponding in number with the switch blocks of each punch action and in length with the assemblage of such actions, and adapted when advanced to retract all the switch blocks which have been set, and when the retractor is retracted, to permit said blocks to be set.

On one of the rock shafts F^1 is an operating arm F^6 , operably connected with the transmission by means of a rod 77 which is slidably mounted on the basket 2, pinned to said arm and has on its other end an adjusting head 77^a and a roller 78 revolvably mounted thereon and engaging a suitable cam, on the main shaft 15, to actuate and time the retractor F . The functional length of the rod 77 is made adjustable by threading its end and making a corresponding female thread in the head 77^a so that by screwing the head more or less on the rod its functional length can be adjusted to properly locate the arc of motion of the retractor rods F^5 relatively to the operative and non-operative positions of the switch blocks 50^s .

The retractor rods F^5 are utilized as abutments for the switch-springs 50^x , which, when applied to switch blocks, tend to close them against said rods (Fig. 4). Card-perforating machines, as heretofore built, comprise a great number of punch actions, arranged in series, to be sure, but each having its individual striking key, and therefore not facile in operation; and my invention consists in substituting, for such an unmechanical assemblage of independent units, an organization comprising a plurality of successive series of punch actions and a key mech-

anism comprising the minimum number of striking keys and key actions, and therefore of the utmost simplicity in construction and facility in operation and adapted to select, 5 co-act with and cause the operation of punches in successive punch action series.

I claim as new, and desire to protect by Letters Patent:

1. In a perforating machine, a frame, a 0 plurality of punch-action series mounted thereon, a key-action mechanism movable on said frame and comprising a key-action series corresponding with one of and adapted to co-act with said successive punch-action 5 series and means for traversing said key-action mechanism.

2. In a perforating machine, a frame, a 10 plurality of punch-action series mounted thereon, a key-action mechanism movable on said frame and comprising a key-action series corresponding with one of and adapted to co-act with said successive punch-action series and feed mechanism, operably connected with said key-action mechanism and 25 adapted, when a key is struck, to initiate feed motion of said mechanism and arrest it in co-acting position relatively to the succeeding punch-action series.

3. In a perforating machine, a frame, a 30 plurality of punch-action series mounted thereon, a key-action mechanism movable on said frame and comprising a key-action series corresponding with and adapted to co-act with said successive punch-action series 35 and a skip key-action adapted to initiate the advance of said key-mechanism; and a spring-actuated feed mechanism adapted to advance said key mechanism.

4. In a perforating machine, a frame, a 40 plurality of punch-action series mounted thereon, a key-action mechanism movable on said frame and comprising a key-action series corresponding with and adapted to co-act with said successive punch-action series 45 and a skip key-action adapted to initiate the advance of said key-mechanism, a spring-actuated feed mechanism adapted to advance said key mechanism, and an escapement mechanism adapted to control the feed of 50 said carriage.

5. In a perforating machine, a frame, a 55 plurality of punch-action series mounted thereon, a key-action mechanism movable on said frame and comprising a key-action series corresponding with and adapted to co-act with said successive punch-action series and a skip key-action adapted to initiate the advance of said key-mechanism, a spring-actuated feed mechanism adapted to advance 60 said key mechanism, and an escapement mechanism adapted to initiate the advance of said key-mechanism and to stop it in co-acting position with successive punch-action series.

6. In a perforating machine, a frame, a 65 plurality of punch-action series mounted thereon, a key-action mechanism movable on said frame and comprising a key-action series corresponding with and adapted to co-act with said successive punch-action series 70 and a skip key-action adapted to initiate the advance of said key-mechanism, a spring-actuated feed mechanism adapted to advance said key, and an escapement mechanism operably connected with said key-action 75 and adapted when one of said actions is operated to initiate the advance of said carriage and to stop it in co-acting position with the succeeding punch-action series and a feed mechanism connected with and 80 adapted to advance said carriage.

7. In a perforating machine, a frame; a 85 plurality of punch-action series mounted thereon; a key mechanism movable on said frame and comprising a key-action series 90 corresponding with one of and adapted to co-act with said punch-action series successively, and a skip key-action, an escapement mechanism operably connected with said key-action and adapted when a key of 95 said actions is struck to initiate the advance of said carriage and stop it in co-acting position with the succeeding punch-action series, and when said skip key-action is held down to permit the carriage to be advanced; and a feed mechanism connected with and adapted to advance said carriage.

8. In a perforating machine, a punch-action comprising a punch and an extension thereof both substantially axially movable 100 and a settable member which normally lies out of the path followed by said punch and its extension to permit a free motion thereof and which is adapted to be set in said path to limit said motion.

9. In a perforating machine, a punch-action comprising a punch and an extension thereof both substantially axially movable, a settable member which normally lies out of the path followed by said punch and its 110 extension to permit free motion thereof and which is adapted to be set in said path to limit said motion, and a spring manually adjustable on said settable member and adapted to hold it in its operative position. 115

10. In a perforating machine, a punch-action comprising a punch and an extension thereof both substantially axially movable, a settable member which normally lies out of the path followed by said punch and its 120 extension to permit free motion thereof and which is adapted to be set in said path to limit said motion; a support for said settable member; and a friction engagement between it and its support adapted to hold it in non-operative and in its operative position.

11. In a perforating machine, a series of punch-actions each comprising a punch and

an extension thereof both substantially axially movable and a settable member which normally lies out of the path followed by said punch and its extension to permit free motion thereof and which is adapted to be set in said path to limit said motion; and a retractor normally disengaged from and adapted to be advanced to return all said settable members to their inoperative positions and to be itself returned to its normal position.

12. In a perforating machine, a series of punch-actions each comprising a punch and an extension thereof both substantially axially movable and a settable member which normally lies out of the path followed by said punch and its extension to permit free motion thereof and which is adapted to be set in said path to limit said motion; and a retractor comprising a member adapted to move substantially parallel with, and normally disengaged from and adapted to be advanced to engage said settable members and return them to their inoperative position and to be itself returned to its normal position.

13. In a perforating machine, a series of punch-actions each comprising a punch and an extension thereof both substantially axially movable and a settable member which normally lies out of the path followed by said punch and its extension to permit free motion thereof and which is adapted to be set in said path to limit said motion; and a retractor comprising parallel motion members and retractor rods therein and normally disengaged from said settable members, said retractor adapted to be advanced and engage said settable members with said rods and return them to their normal position and be itself returned to its normal position.

14. In a perforating machine, a plurality of series of punch-actions, each punch-action comprising a punch and an extension thereof both substantially axially movable and a settable member which normally lies out of the path followed by said punch and its extension to permit free motion thereof and which is adapted to be set in said path to limit said motion; and a retractor comprising parallel moving members normally disengaged from said settable members and adapted to be advanced and return said settable members to their inoperative position and to be itself returned to its normal position.

15. In a perforating machine, a frame; a reciprocating member mounted thereon; means to reciprocate said member; a die-plate and a guide-plate on said member separated to admit cards between them and perforated with series of registering holes; a punch supporting plate on said frame and likewise perforated; a guide-plate on said

frame correspondingly but divergently perforated; members transverse on said frame; and series of key-actions each comprising a punch located in registering holes in said supporting plate on the frame and the guide-plate on said movable member, a punch extension extending said punch through a hole in said guide-plate on said frame, and a settable member pivoted on one of said transverse frame members, said settable member normally lying out of the path followed by said punch and its extension to permit free motion thereof and adapted to be set in said path to limit said motion.

16. In a perforating machine, a frame; a reciprocating member mounted thereon; means to reciprocate said members; a die-plate and a guide-plate on said member separated to admit cards between them and perforated with series of registering holes; a punch-supporting plate on said frame and likewise perforated; a guide-plate on said frame correspondingly but divergently perforated; members transverse on said frame; series of key-actions each comprising a punch located in registering holes in said supporting plate on the frame and the guide-plate on said movable member, a punch extension extending said punch through a hole in said guide-plate on said frame, and a settable member pivoted on one of said transverse frame members, said settable member normally lying out of the path followed by said punch and its extension to permit free motion thereof and adapted to be set in said path to limit said motion.

17. In a perforating machine, a key-action adapted to co-act with and set settable members in successive punch-actions and comprising a striking key, a pin, and a lever operably connecting said key and pin, and means for supporting the aforesaid members in their operative position.

18. In a perforating machine, a frame; runways on said frame; a key-action carriage mounted on said runways; a spring feed mechanism adapted to advance said carriage; a series of key-actions mounted on said carriage each comprising a striking key, a pin adapted to co-act with and set settable members of punch-actions, and a lever connecting said striking key and pin; a rock shaft mounted in said carriage and operably connected with said key action; escapement pawls connected with said rock shaft; a ratchet wheel and a pinion connected thereto revolubly mounted on said carriage; and a rack fixed

on said frame and in engagement with said pinion.

19. In a perforating machine, a frame, runways on said frame; a key-action carriage mounted on said runways; a spring feed mechanism adapted to advance said carriage; a series of record key-actions mounted on said carriage each comprising a striking key, a pin adapted to co-act with and set settable members of punch-actions, and a lever connecting said striking key and pin; a skip key-action on said carriage comprising a striking key and a lever; a rock shaft mounted in said carriage and operably connected with said record key actions; escapement pawls connected with said rock shaft; a ratchet wheel and a pinion connected thereto revolubly mounted on said carriage, and a rack on said frame in engagement with said pinion.

20. In a perforating machine, a frame, runways on said frame, a key-action carriage mounted on said runways, a spring feed mechanism adapted to advance said carriage, a series of record key-actions mounted on said carriage each comprising a striking key, a pin adapted to co-act with and set settable members of punch-actions and a lever connecting said striking key and pin, a skip key-action on said carriage comprising a striking key and a lever, a rock shaft mounted in said carriage and operably connected with said record key-action, a final release pawl on said rock shaft and a pivotally mounted initial release pawl, a member on said final release pawl adapted to engage said initial release pawl, a member on said initial release pawl adapted to engage said skip key-action, a ratchet wheel and a pinion connected thereto revolubly mounted on said carriage, and a rack on said frame in engagement with said pinion.

21. In a perforating machine, a frame, a plurality of punch-action series mounted thereon, a settable member in each punch-action, a key mechanism slidably mounted on said frame and comprising a carriage and a series of key-actions mounted in said carriage and adapted to co-act severally with settable members in said punch-action series, means for automatically advancing said carriage and adjustable stops adapted to limit its traverse.

22. In a key-action carriage for perforating machines, cheek-members adapted for slidably mounting said carriage and for the mounting of revoluble members, a pair of transverse plate members united to said cheek-members, registering holes in said plate members, key-action pins therein, key-action levers pivoted on said upper plate and severally connecting the pin and stem of key-actions, a rock shaft revolubly mounted in said cheek members and an escapement

mechanism operably connected with said rock shaft.

23. In a key-action carriage for perforating machines, cheek members, transverse plate members uniting said cheek members, a series of key-actions each comprising a striking key, a pin and a lever connecting said key and pin, a rock shaft; bearings therefor in said cheek members, a shaft head in one of said bearings and angularly fixed to said shaft, a final-release pawl fixed on said shaft head, a pivotally mounted initial-release pawl, a revolubly mounted ratchet wheel and a pinion connected therewith and adapted to engage a fixed rack.

24. In a perforating machine key-action mechanism adapted to co-act with and set settable members of successive punch-actions, a carriage adapted to be slidably mounted on said carriage, a series of key-actions, a rock shaft operably connected with said key-actions, a ratchet wheel and a pinion connected thereto and adapted to engage a fixed rack, a loosely mounted initial-release pawl, a spring adapted to pull said pawl out radially and also to move it to engaging position relatively to said ratchet wheel, a final-release pawl on said shaft adapted to engage and be disengaged from said ratchet wheel and means for connecting and disconnecting said final-release pawl and initial-release pawls.

25. In a perforating machine, a frame; a plurality of punch-action series and a fixed rack on said frame; a key-action mechanism slidably mounted on said carriage and comprising a record key-action series corresponding with a punch-action series and adapted to co-act with and set settable members of successive punch-action series, a skip key-action a feed adapted to advance said carriage, an escapement mechanism operably connected with said key-actions and adapted to initiate and stop the traverse of said carriage when one of said keys is struck and when said skip key is held down to permit the advance of said carriage; a skip-stop mechanism mounted on said frame and adjustable stops thereon, said skip-stops mechanism normally in inoperative position, operably connected with said skip-key action and adapted to be advanced into operative position when said skip-key action is operated.

26. In a perforating machine, a frame; a plurality of punch-action series and a fixed rack on said frame; a key-action mechanism slidably mounted on said carriage and comprising a record key-action series corresponding with a punch-action series and adapted to co-act with and set settable members of successive punch-action series, and a skip-key action, a feed adapted to advance said carriage, an escapement mechanism op-

erably connected with said key-action and adapted to initiate and stop the traverse of said carriage when one of said keys is struck and when said skip-key is held down to 5 permit the advance of said carriage, and a skip-stop mechanism comprising a rocking member pivoted on said frame and extending parallel with the traverse of said carriage, stops adjustable on said rocking 10 member, said rocking member and stops being normally in non-operative position and an operable connection between said rocking member and said skip-key action adapted to cause said rocking member and adjusted 15 stops therein to advance into engaging position relatively to said carriage when said skip-key is operated.

27. In a perforating machine, a frame; a plurality of punch-action series and a fixed 20 rack on said frame; a key action mechanism slidably mounted on said carriage and comprising a record key-action series corresponding with a punch action series and adapted to co-act with and set settable 25 members of successive punch-action series, a skip-key action, a feed adapted to advance said carriage, an escapement mechanism operably connected with said key-actions and adapted to initiate and stop the 30 traverse of said carriage when one of said keys is struck and when said skip-key is held down to permit the advance of said carriage; and a skip-stop mechanism comprising a rocking member pivoted in said frame 35 and extending parallel with the traverse of said carriage and thereon a rocker arm operably connected with said skip-key action, a rack corresponding with the aforesaid fixed rack, a stop-support, and adjustable stops adapted to engage said rack and to be linearly adjusted and angularly advanced and retracted; said skip-stop mechanism being normally in non-operative position and adapted to be advanced and move 45 its stops into operable position relatively to said carriage, when said skip-key action is operated.

28. In a perforating machine, a frame, main shaft mounted thereon and connected 50 with a source of power, a cam on said shaft, a plurality of punch-actions series each punch-action comprising a punch, a punch rod and a settable member normally inoperatively located and adapted to be 55 set in its operative position by the operation of a key-action, a retractor normally in neutral position and adapted to be advanced to return settable members aforesaid to their nonoperative positions, and an 60 adjustable connection between said cam and retractor, an arm on said retractor, a reciprocating rod connecting said arm and cam and an adjustable head on said rod.

29. In a perforating machine, a frame, a

plurality of punch-action series mounted on 65 said frame, each such series comprising a number of punch-actions arranged in a line, and a key-action mechanism slidable on said frame and comprising a series of key-actions corresponding with a punch-action 70 series and adapted to cause the operation of punch-actions in successive series.

30. In a perforating machine, a frame, a plurality of punch-action series mounted on 75 said frame, each such series comprising a number of punch-actions arranged in a line, and a key-action mechanism slidable on said frame and comprising a series of key-actions corresponding with a punch-action 80 series, arranged in a plurality of lines and adapted to cause the operative punch-actions in successive series.

31. In a perforating machine, a frame, a reciprocating member comprising a die-plate and a guide-plate separated to admit 85 cards between them and perforated with series of registering holes, a punch-supporting plate fixed to said frame and similarly perforated, series of punches located in such holes in said guide-plate on the reciprocating member and said supporting-plate on the frame, parallel-sided heads on said punches and bars fixed to said frame and extending parallel with and adjacent to 90 said heads of punches in said several series. 95

32. In a perforating machine, a frame, a reciprocating member comprising a die-plate and a guide-plate separated to admit 100 cards between them and perforated with series of registering holes, a punch-supporting plate fixed to said frame and similarly perforated, series of punches located in such holes in said guide-plate on the reciprocating member and said supporting-plate on the frame, parallel-sided heads on said 105 punches and a grill fixed to said frame and comprising bars extending parallel with and adjacent to said heads of punches in said several series.

33. In a perforating machine, a frame, a reciprocating member comprising a die-plate and a guide-plate separated to admit 110 cards between them and perforated with series of registering holes, a punch-supporting plate fixed to said frame and similarly 115 perforated, series of punches located in such holes in said guide-plate on the reciprocating members and said supporting-plate on the frame, parallel sides on said punches and bars fixed on said guide-plate 120 of said reciprocating members and extending adjacent and parallel to said parallel punch-sides in said several series.

34. In a perforating machine, a frame, a reciprocating member comprising a die-plate and a guide-plate separated to admit 125 cards between them and perforated with series of registering holes, a punch-support-

ing plate fixed to said frame and similarly perforated, series of punches located in such holes in said guide-plate on the reciprocating members and said supporting-
5 plate on the frame, parallel sides on said punches and a grill fixed on said guide-plate of said reciprocating member and compris-

ing bars extending adjacent and parallel to said parallel punch-sides in said several series.
